(57) **CLAIM**

The ornamental design for a low drag antenna, as shown and described.

DESCRIPTION

FIG. 1, is an isometric view of a low drag antenna showing my new design:

FIG. 2, is a side elevational view of the case thereof:

FIG. 3, is a front view of the case thereof, as seen from the left hand side of FIG. 2;

FIG. 4, is top view of the case thereof; and,

FIG. 5, is a bottom view of the case thereof.

The broken lines in FIG. 5 represent portions of the antenna that form no part of the claimed design.
